US0D1053216S

(12) **United States Design Patent** (10) Patent No.: **US D1,053,216 S**
Chen et al. (45) Date of Patent: ** Dec. 3, 2024

(54) **DISPLAY SCREEN OR PORTION THEREOF WITH ANIMATED GRAPHICAL USER INTERFACE**

(71) Applicant: **Willand (Beijing) Technology Co., LTD.**, Beijing (CN)

(72) Inventors: **Zichong Chen**, Beijing (CN); **Zhuo Lv**, Beijing (CN); **Chen Chen**, Beijing (CN); **Pan Wang**, Beijing (CN)

(73) Assignee: **WILLAND (BEIJING) TECHNOLOGY CO., LTD.** (CN)

(**) Term: **15 Years**

(21) Appl. No.: **35/518,540**

(22) Filed: **Jul. 24, 2023**

(80) **Hague Agreement Data**

Int. Filing Date: **Jul. 24, 2023**

Int. Reg. No.: **DM/231764**

Int. Reg. Date: **Jul. 24, 2023**

Int. Reg. Pub. Date: **Oct. 6, 2023**

(30) **Foreign Application Priority Data**

Feb. 28, 2023 (CN) 202330080548.1

(51) LOC (14) Cl. **14-04**

(52) U.S. Cl.

USPC **D14/488; D14/485**

(58) **Field of Classification Search**

USPC D14/489-495, 485-488

(57) **CLAIM**

The ornamental design for a display screen or portion thereof with animated graphical user interface, as shown and described.

DESCRIPTION

1.1 : Front
1.2 : Front
1.3 : Front
1.4 : Front
1.5 : Front
1.6 : Front
1.7 : Front
1.8 : Front
1.9 : Front

The appearance of the animated image sequentially transitions between the images shown in reproductions **1.1** to **1.9**; the process or period in which one image transitions to another image forms no part of the claimed design; the broken line rectangle illustrates the display screen or portion

(Continued)

thereof and forms no part of the claimed design, whereas all other broken lines show a part of the claimed design.

1 Claim, 9 Drawing Sheets

Start Visual Mapping

When Raptor recognizes a clear lawn border, it can start visual mapping and automatically drive along the border. If it encounters scenes such as low light or unclear edges, as well as the dangerous scene swimming pools, please switch to manual mapping in time.
